CLAIM

We claim, the ornamental design for a display screen portion with icon, as shown and described.

DESCRIPTION

FIG. 1 is a front view of a display screen portion with icon showing our new design;

FIG. 2 is a second embodiment thereof;

FIG. 3 is a third embodiment thereof; and,

FIG. 4 is a fourth embodiment thereof.

The broken lines illustrating portions of the display screen portion with icon are for environmental purposes only and form no part of the claimed design.
